SPARKING PLUG FOR INTERNAL
COMBUSTION ENGINES

George Edward Woods-Humphrey, Chelsea, London, and Henry Leonard Hall, Streatham, London, England

Application January 4, 1934, Serial No. 705,246
In Great Britain January 6, 1933

5 Claims. (Cl. 123—169)

This invention relates to sparking plugs for internal combustion engines and has for its object the provision of means which will enable the plug without alteration to be equally suitable for use in very hot or very oily engines.

Hitherto it has been held that characteristically different types of plugs are essential for efficient operation in hot and oily engines respectively, and because of this widely accepted theory, manufacturers of sparking plugs offer and recommend for use in hot engines plugs which differ very considerably in construction from those they offer for use in oily engines.

It is proposed to attain the object of this invention and to overcome the disadvantages of the present plugs by the combination with said plugs of means, interposed between and formed separately from the engine cylinder, which means will prevent said plugs from reaching unduly high temperatures and trap oil and other foreign matter which may be suspended in the combustible gases which are caused to pass through a labyrinth before reaching the igniter chamber in which the sparking points are located.

25 In the accompanying drawing which illustrates this invention:

Figure 1 is a longitudinal elevation, partly in section, of a sparking plug with an igniter protector constructed in accordance with one embodiment of this invention, and,

Figures 2, 3 and 4 are similar views illustrating three further embodiments.

Referring to Figure 1, the igniter protector comprises a hollow cylindrical internally screw threaded body part 1 furnished at one end with an externally screw threaded chambered extension 2 of reduced diameter adapted to be secured in the engine cylinder in place of the usual sparking plug. The part 1 of the igniter is adapted to receive (a) a baffle 3, part of which is adapted to enter the extension 2 so as to form a chamber 4 and (b) the screw threaded end of a sparking plug 5 of any suitable type. The outer end of the extension 2 and the end wall of the chamber 4 are formed conical as shown and said extension is further provided with a centrally and axially disposed aperture 6 opening into the chamber 4. The baffle 3 is furnished with a conical depression 7 and with a plurality of longitudinally disposed passages 8 adapted to place the chamber 4 in communication with an igniter chamber 9 formed between the end of the sparking plug 5 and the inner end of baffle 3. The aperture 6, chamber 4 and passages 8 combine to form a labyrinth which reduces to the minimum the risk of oil

or other foreign matter reaching the igniter chamber 9.

In operation the combustible mixture within the engine cylinder passes through the aperture 6 and into the conical depression 7 which deflects it onto the walls of the chamber 4 on which are deposited most or all of any foreign matter it may be carrying. From chamber 4 the mixture passes through the passages 8, which tend to trap any remaining particles of foreign matter, to the igniter chamber 9. After the mixture is exploded by the sparking plug 5 the burning gases flow in the opposite direction and drive out any foreign matter which has been trapped in the labyrinth.

It will be seen from the foregoing that the functioning of the igniter protector defers indefinitely fouling of the sparking plug by oil or other foreign matter and it will also be seen that the small and tortuous passages in the labyrinth greatly reduce the intensity of the attack of the burning gases on the sparking points of the plug 5 and also that this provision for keeping the firing points of the sparking plug at a reasonably low temperature is aided by placing the firing points as remote from the engine cylinder as is desirable and also by providing relatively heavy masses of metal which ensure good heat-flow from the baffle 3 to the body 1 and thereby to the atmosphere and also from said body through extension 2 to the body of the engine cylinder.

When the piston of the engine is at the end of the induction stroke the interior of the igniter protector contains a quantity of burnt gas which, on the compression stroke, is compressed into the space behind the firing points and forms a cushion of inert gas which minimizes the attack of the burning gases on the adjacent surfaces of the sparking plug; it will be apparent that the quantity of burnt gas trapped in this way must be adjusted to ensure the presence of combustible mixture at the firing points and in the labyrinth.

It follows that this combination of provisions results in a sparking plug which will keep sufficiently cool in a "hot" engine and will also have great resistance to oiling up in any engine.

In the modification illustrated in Figure 2, the baffle 3 is formed integrally with the body 1, and the labyrinth is formed by the axial passage 6, radial passages 10, annular chamber 11 provided around the extension 2 and angular passages 12 which open into the igniter chamber 9.

In the modification illustrated in Figure 3, the baffle 3 is formed integrally with the extension 2 and is provided with the conical depression 7 and angularly disposed passages 13 opening into the

igniter chamber 9. The end 14 of the extension 2 is in this case formed separately and is secured in position in any convenient manner, such as by spinning over the upper edge 15 of the top of the extension 2. In this construction the sparking plug comprises a screw threaded part 16 and a central electrode 17, the outer or negative points 18 which coat with the electrode 17 being provided on the baffle 3.

10 The modifications illustrated in Figure 4 is similar to Figure 3, but in this case the baffle 3 carrying the negative points 18, is formed separately from the extension 2 and is secured therein in any convenient manner and the conical end 14 is formed integrally with the extension 2.

15 The operation of the devices illustrated in Figures 2, 3 and 4 is the same as that described in connection with Figure 1 and further description is therefore unnecessary.

20 What we claim is:—

1. An ignition device for use in internal combustion engines, comprising in combination, an igniter unit, and an igniter protector comprising a body portion in which the igniter unit is screwed, a screw threaded extension adapted to be screwed into the engine cylinder, an axially disposed aperture in the end of said extension, a baffle within said extension, a chamber between one face of said baffle and the inner wall of said axially disposed aperture, a conical recess in that end of the baffle forming the opposite wall of said chamber, an igniter chamber formed between the end of the igniter unit and the other face of said baffle and a plurality of passages in said baffle arranged out of alignment with said axially disposed aperture constituting a labyrinth connecting the first named chamber with the igniter chamber.

2. In an ignition device for use in internal combustion engines the combination of an igniter unit comprising a sparking plug and an igniter protector comprising an internally screw threaded body portion in which the sparking plug is screwed, an externally screw threaded extension on said igniter protector adapted to be screwed into the engine cylinder, an axially disposed aperture in the end of said extension, a partially screw threaded baffle screwed into said body portion, a conical recess in one end of said baffle, a chamber formed between one face of said baffle and the inner wall of said axially disposed aperture, an igniter chamber formed between the other face of said baffle and the end of the sparking plug, and, a plurality of passages in said baffle arranged out of alignment with the axially disposed aperture in the end of the extension constituting with said aperture and the first named chamber a labyrinth leading to the igniter chamber.

3. In an ignition device for use in internal combustion engines, the combination of an igniter unit comprising a sparking plug and an igniter protector comprising an internally screw threaded

ed body portion in which the sparking plug is screwed, an externally screw threaded extension on said igniter protector adapted to be screwed into the engine cylinder, a baffle within and formed integrally with said extension, an igniter chamber on one side of said baffle, an axially disposed aperture in the end of said extension on the other side of said baffle, an annular chamber around said extension, a plurality of radially disposed passages in said extension adjacent said baffle, and communicating with said annular chamber and a plurality of angularly disposed passages in said baffle connecting said annular chamber with the igniter chamber.

4. In an igniter device for use in internal combustion engines, the combination of an igniter unit comprising an externally screw threaded body and a centrally disposed electrode secured therein and an igniter protector comprising an internally screw threaded body portion in which the externally screw threaded body of the igniter unit is screwed, an externally screw threaded extension on said igniter protector adapted to be screwed into the engine cylinder, a baffle within and formed integrally with said extension, a plurality of sparking points on one side of said baffle arranged to co-operate with the centrally disposed electrode, an igniter chamber in which said sparking points and electrode are located, a conical recess formed in the opposite side of said baffle, a conical end piece fitted to the end of said extension, an axially disposed aperture in said end piece, a chamber, the end walls of which are formed by the conical recess in the baffle and the inner wall of the conical end piece and a plurality of passages in said baffle connecting the last named chamber with the igniter chamber.

5. In an igniter device for use in internal combustion engines, the combination of an igniter unit comprising an externally screw threaded body and a centrally disposed electrode secured therein, and an igniter protector comprising an internally screw threaded body portion in which the externally screw threaded body of the igniter unit is screwed, an externally screw threaded extension on said igniter protector adapted to be screwed into the engine cylinder, an axially disposed aperture in the end of said extension, a baffle within and formed separately from said extension, a plurality of sparking points on one side of said baffle arranged to co-operate with the centrally disposed electrode, an igniter chamber in which said sparking points and electrode are located, a conical recess formed in the opposite side of said baffle, a chamber between the side of said baffle last named and the inner end wall of the extension and a plurality of passages in said baffle connecting the last named chamber with the igniter chamber.
